UNITED STATES PATENT OFFICE

108,654

DESIGN FOR A LIGHTING FIXTURE

Kurt Versen, New York, N. Y.

Application January 8, 1937, Serial No. 66,950

Term of patent 14 years

To all whom it may concern:

Be it known that I, Kurt Versen, a citizen of the German Reich, having taken out first papers for citizenship in the United States, residing at New York, New York, have invented a new, original, and ornamental Design for a Lighting Fixture, of which the following is a specification, reference being had to the accompanying drawing, which forms a part thereof, in which:

Fig. 1 is a perspective view of a lighting fixture embodying my novel design; and

Fig. 2 is a plan view of the same fixture as it would appear from the bottom.

The design is characterized by the combination of the relatively broad horizontal bowl convex toward the bottom side and with a relatively slight radial curvature and a ring of contrasting texture and color at the outer edge of said bowl also convex toward the lower side but having much sharper radial curvature, together with the other features of the lighting fixture substantially as shown.

I claim:

The ornamental design for a lighting fixture substantially as shown and described.

KURT VERSEN.
